CASTING MACHINE

Robert H. Orr, Birmingham, Ala., assignor to
 Tennessee Coal, Iron and Railroad Company, a
 corporation of Tennessee

Application April 21, 1945, Serial No. 589,515

3 Claims. (Cl. 22—57)

1

The present invention relates to casting machines which, while not limited thereto, are peculiarly well suited for casting elongated tin anodes used in electrolytic tinning processes.

The primary object of the invention is to provide improved means for casting metal objects in separable mold sections equipped with power means for separating the sections and power means for ejecting the castings from the molds.

Another object of the invention is to provide supporting means including power-operated mechanism for shifting one of the mold sections relatively to the other and for imposing pressure to hold the mold sections in tight engagement with one another when the latter are in closed casting position.

A further object of the invention is to provide power means for ejecting a casting from the mold after the sections thereof have been separated.

An additional object is to provide a conveyor table in a position to receive the castings ejected from the mold by said ejector means.

Another object is to provide means for tiltably supporting the conveyor and power means for tilting such supporting means.

A further object is to combine and coordinate the various instrumentalities shown and described, in such manner that they individually and jointly perform the functions hereinafter set forth.

The above and further related objects are made available by the embodiment of the invention herein shown.

For a more complete disclosure of the invention, reference should be made to the following detailed description, the accompanying drawings, and the appended claims.

In the drawings:

Figure 1 is a side elevation of a casting machine embodying the herein claimed invention.

Figure 2 is a sectional elevation of Figure 1, taken on line II—II of Figure 1.

Figure 3 is a view similar to Figure 2, illustrating the position of movable mold sections after they have been separated from complementary fixed sections, and also illustrating a different position of certain elements of the casting ejector mechanism.

Figure 4 is a plan view of Figure 1.

Figure 5 is a diagram showing the piping and valves controlling the operation of the several air cylinders which actuate the various mechanisms herein described.

Referring in detail to the embodiment of the invention illustrated, numerals 10—10 represent

side frames which are spaced apart by transverse cross members 12—12 and longitudinal members 14—14. A transverse cross member 16, rigidly secured to frame members 10—10, carries ears 18 which support a pivot pin 20 which passes through a lug 22 depending from a cross member 24 secured to the side angle bars 26 constituting the main frame elements of a conveyor table indicated as a whole at 28. Journalled between the angles 26 of the conveyor table 28 is a series of rotatably mounted rolls 29 collectively constituting a roller table over which the castings are adapted to be pushed or to roll by gravity when the table is inclined.

5 A fluid pressure cylinder 30 fulcrumed on a pin 32 carried by a bracket 33 is secured to the frame structure. Within the cylinder 30 is a piston carrying a rod 34 pivotally connected by a pin 36 to a lug depending from the under side of the conveyor table. As thus arranged, it is apparent that by supplying pressure fluid to either end of the cylinder 30, the conveyor table can be rocked about the pivot pin 20 so as to vary the angularity thereof.

10 Supported at an angle oblique to the uprights 10 of the frame are a plurality of fixed brackets 38 to which are secured fixed mold sections 40 of angular cross-sectional or L shape, as shown. Slidably guided on the fixed brackets 38 are supporting heads 42 which are connected by pins 44 with upstanding ears 46 secured to movable L-shaped mold sections 48 which are complements of the fixed mold sections 40, the latter being provided with notched portions 50 forming seats for coaction with the tongue extremities 52 of the movable sections 48. The heads 42 make a comparatively loose sliding fit on the guides of the brackets 38, and said movable mold sections 48 are suspended from respective pairs of 15 adjustable links 54 connected by pins 56 with the cranks 58 secured to rock shafts 62. At one end of each shaft, each crank 58 has a bell crank arm 60 and 60^a respectively. The shafts 62 are mounted in brackets 64 secured fixedly to the uprights 10 of the frame of the machine. The arm 60 of the right-hand bell crank of Figures 2 and 3 is connected by a pin 70 to the clevis end of a piston rod 72 extending from a piston 74 operating in the cylinder 68. The left-hand bell 20 crank arm 60^a of Figures 2 and 3 is connected to a pin 66 carried by ears at the left end of the cylinder 68. When fluid pressure is admitted to the left-hand end of the cylinder, as viewed in Figure 2, the piston 74 will be forced outwardly and thus materially increase the distance between

the pins 66 and 70, thereby rocking the cranks 58 so as to lift the supporting heads 42 to the position of Figure 3 and thus separate the upper mold sections 48 from the lower mold sections 40. When fluid pressure is admitted to the right end of the cylinder 68, the piston 74, through the connections shown, will shift the mold parts to the closed position of Figure 2, and forcibly hold them in such position.

A pair of wedge members 76 having converging faces 78 cooperating with wedge faces 80 formed on the upper mold sections 48 are provided with lateral extensions 82 which are pivotally connected with the pins 44. The pins 44 connect with the links 54 and pass loosely through slots 84 in the ears 46, so as to provide for a slight amount of lost motion to provide a clearance between the wedge faces 78 and the wedge projections 80, as shown in Figure 3, when the mold sections are separated. When the mold sections are closed, as illustrated in Figure 2, the wedge members 76 are held by the pressure of the piston in cylinder 68 in a manner to firmly hold the tongue portions 52 of the movable mold sections 48 against the grooved seats 58 of the fixed mold sections 40. The conjoint action of the fluid pressure means and the wedge members described provides an extremely tight joint between the interfitting separable mold parts, and thus insures the formation of clean-cornered castings, which is highly desirable in the casting of tin anodes for use in an electrotinning process.

For ejecting the castings from the mold sections, I provide cylinders 86 having pistons 88 working therein carrying ejector rods 90 which are adapted to be moved from the position of Figure 2 to the position of Figure 3 so as to strip the castings C from the molds and to transfer them onto the rollers 29 of the conveyor table.

As shown in Figure 5, I provide a valve and piping layout whereby the operations of all the operating cylinders can be controlled from a common station convenient to the operator. As illustrated, 92 represents an air line connected to a suitable supply of compressed air (not shown). Said air line is connected with four individual four-way valves 94, 96, 98, and 100.

The valve 94, which controls the conveyor tilting cylinder 30, is a four-way valve without neutral position, and is connected with opposite ends of cylinder 30 by pipes 94^a and 94^b, as shown.

Valves 96 and 98, which control the ejector cylinders 86, are spring biased four-way valves which automatically return to position after each operation. They are connected to the opposite ends of cylinders 86 by respective pipes 96^a, 96^b, 98^a, and 98^b, as shown.

Valve 100, which controls the mold opening and closing cylinder 68, is a four-way valve without neutral position, and it is connected with the opposite ends of cylinder 68 by pipes 100^a and 100^b, as shown.

With the arrangement of operating cylinders connected with their respective control valves as shown and described, interlocks between the valves are not necessary, since the valves 96 and 98 which control the cylinder 86 for ejecting the cast anodes from the molds are returned automatically to closed position by suitable springs, not shown, thus preventing the ejector rods 90 from interfering with the lowering of the upper mold sections 48. In the event that the valve 94 should be inadvertently operated at any time during the pouring of metal into the molds, no harm would result, since such act would merely

shift the position of the conveyor table about its pivotal support 20.

From the foregoing it will be apparent that in the normal operation of the casting machine illustrated, molten metal may be poured into the molds at the point 93. At the time of casting, it will be understood, there will be pressure on the right side of the piston 74 in the cylinder 68, so as to thus cause the cranks 58, arms 60, 60^a, and links 54 to press down on the wedge members 76 and thereby forcibly hold the upper movable mold sections 48 in firm engagement with the lower fixed sections 40. After the casting has solidified within the mold sections, air pressure will be admitted to the left end of the cylinder 68, as viewed in Figures 2 and 3, to thus lift the links 54, and through the connections described, raise the upper mold sections 48. After the mold sections are separated, the operator will shift the valves 96 and 98 to cause the ejection of the castings onto the conveyor table, which at this time will be inclined at the same angle as the mold sections. Thereafter when the ejector rods 90 have been retracted, the operator may operate the valve 94 to shift the conveyor to substantially horizontal position to arrest or control the gravity travel of the castings along the conveyor table, as described.

While I have described quite precisely a preferred practical embodiment of the invention, it is not to be construed that I am limited thereto, since various modifications may be made within the scope of the appended claims.

I claim:

35. 1. A casting machine comprising a frame, a pair of lower mold sections of L-shape in cross-section rigidly supported on said frame, a pair of complementary movable upper mold sections of inverted L-shape in cross-section, uprights 40 fixed to said frame and arranged in opposed pairs alongside each of said lower mold sections, a plurality of heads, one of which is slidable on each of said uprights, a pair of rock shafts rotatably supported on said frame and carrying cranks 45 operatively connected through said upper mold sections to said heads, mechanism for rocking said shafts, and wedge means responsive to movement of said cranks and having lost motion connections with said upper mold sections for firmly holding said upper mold sections in closed position on said lower mold sections.

2. A casting machine comprising a frame, a conveyor on said frame, a pair of lower mold sections of L-shape in cross-section, one of which 55 is rigidly supported on said frame at each side of said conveyor to discharge castings thereto, a pair of complementary movable upper mold sections of inverted L-shape in cross-section, uprights fixed to said frame and arranged in opposed pairs alongside each of said lower mold sections, a plurality of heads, one of which is slidable on each of said uprights, a pair of rock shafts rotatably supported on said frame and carrying cranks 60 operatively connected through said upper mold sections to said heads, mechanism for rocking said shafts and thereby raising and lowering said upper mold sections, and wedge means responsive to movement of said cranks and having lost motion connections with said upper mold sections for firmly holding said upper mold sections in closed position on said lower mold sections.

3. A casting machine comprising a frame, a conveyor on said frame, a pair of lower mold sections of L-shape in cross-section, one of which 75 is

rigidly supported on said frame at each side of said conveyor to discharge castings thereto, a pair of spaced complementary movable upper mold sections of inverted L-shape in cross-section, uprights fixed to said frame and arranged in opposed pairs alongside each of said lower mold sections, a plurality of heads, one of which is slidable on each of said uprights, a pair of rock shafts rotatably supported on said frame and carrying cranks operatively connected through 10 said upper mold sections to said heads, mechanism for rocking said shafts and thereby raising and lowering said upper mold sections, and wedge means spanning the space between said upper mold sections and being connected to opposed pairs of heads and having lost motion connections with said upper mold sections for firmly holding said upper mold sections on said lower mold sections when the upper sections are lowered, said upper mold sections leaving unobstructed the space between said lower mold sections when the upper sections are raised. 20
